[57] CLAIM

The ornamental design for a manually-operated granular fertilizer applicator, as shown and described.

DESCRIPTION

FIG. 1 is a front elevational view of a manually-operated granular fertilizer applicator showing my new design, the rear being a mirror image of, and the adjacent sides being substantially similar in appearance to that shown, and the shaft being shown broken-away for ease of illustration;

FIG. 2 is a reduced perspective view thereof;

FIG. 3 is a top plan view thereof; and

FIG. 4 is a bottom plan view thereof.
